UNITED STATES PATENT OFFICE.

PAUL W. HIRSCH, OF REDFORD, MICHIGAN.

CHAIR.

1,324,503.

Specification of Letters Patent.

Patented Dec. 9, 1919.

Substitute for application Serial No. 20,461, filed April 10, 1915. This application filed April 21, 1919. Serial No. 291,713.

To all whom it may concern:

Be it known that I, PAUL W. HIRSCH, a citizen of the United States, and residing at Redford, in the county of Wayne and State 5 of Michigan, have invented a new and Improved Chair, of which the following is a specification.

This invention relates to chairs and more particularly to those suitable for use in 10 restaurants or other eating places such as dairy lunches where the dishes of food have heretofore been supported by a wide arm of the chair while the patron is eating his lunch.

15 Heretofore it has been necessary to place the food on one or both arms of a chair but my invention has in mind a movable arm for one side of the chair which can be swung around across the front so that the food will 20 be supported by an adjustable arm in front of the diner instead of at his side as is the case with the present chairs on the market in which the food is placed on a fixed arm at one side of the chair.

25 Another object is to provide an apparel hook for the chair on which may be hung apparel of the occupant of the chair, if desired.

30 Further objects are to accomplish the above with as simple and economical design as possible and in a way such that present chairs, now in use, can be supplied with my adjustable arm.

35 With the above and other incidental objects in view my invention further consists in various details of construction and combinations of parts hereinafter more fully described in connection with the drawings which accompany and form part of this 40 specification, and subsequently pointed out in the appended claims.

45 In the drawings, Figure 1 is a perspective view of a lunch chair with my invention applied. Fig. 2 is a similar view but with the adjustable arm shown in position at the front of the chair. Fig. 3 is an enlarged plan view of a portion of the chair, with parts broken away to better show those beneath, and showing by dotted lines, the position of the arm when in front of the chair. Fig. 4 is an elevation of my attachment showing its connection with the chair post. Fig. 5 is a perspective view of the supporting bracket.

50 The chair shown may be of any well

known type provided with no arms whatever. I apply my invention thereto by supporting all the mechanism of it from one of the front legs 1 preferably the right hand one. 2 is a supporting bracket for my attachment which is merely a casting having a foot 3 curved at 4 to fit the leg of the chair. An opposing gripping member 5 is pivoted at 6 by a hinge connection with the foot 3 and both this gripping member 5 and the foot 3 are provided with ears 7 apertured to receive a clamping bolt 8 which, by means of a coöperating nut 9, is used to tightly grip the foot 3 and hinged member 5 around the right hand forward chair leg 1 at any height desired. The upper end of the bracket 2 is provided with an integral flat top 10 extending from the right of the chair, the base of which top portion has extending beneath it an integral supporting web 11 for strength. The shape of the flat top of the bracket 2 can be traced very well from Figs. 1 to 3 and is made of sufficient area to provide a substantial support and slide for the adjustable arm. This top 15 surface 10 of the bracket is provided with a couple of holes 12 down through which from the top extend bolts 13 having a portion 14 of a little larger diameter than the hole in the top of the bracket 10 and having 20 above this portion 14 a head 15 of still larger diameter. These bolts 13 are fastened to the top 10 by nuts 16 screwing on their lower ends so as to hold the bolts in place. The portions 14 of the bolts being of greater 25 diameter than the holes in the top 10 form a shoulder for engaging the top of the bracket 10. The heads 15 of the bolts being still larger in diameter are thus separated from the top of the bracket by sufficient 30 space for the thickness of a sliding member 35 now to be described.

40 17 is a supporting plate for the arm proper of my chair and the shape of this arm can be readily traced from the drawing. The thickness of this plate is just sufficient to fit between the heads 15 of the bolts 13 and the top 10 of the bracket 2. This top 10 slidably supports the plate 17 and the latter is provided with two slots 18 45 through which bolts 13 are passed in assembling the parts on the top of the bracket 2. When this plate 17 is thus mounted on the top 10 of the bracket 2 and the bolts 13 passed through the slots 18 and the holes 50 55 60 65 70 75 80 85 90 95 100 105 110

12 and fastened in place, it will be seen that the plate 17 can slide, supported by the top 10, and that the heads of the bolt projecting over the edges of the slot 18 will retain the plate 17 in place on the bracket top. Thus the top 17 then is free to have either the full line relationship of Fig. 3 at the right of the chair with the bolts 13 at the forward end of the slots 18, or it may have 10 the dot and dash line relationship at the front of the chair in Fig. 3 with the bolts 13 at the other end of the slots 18. It is of course obvious that the plate 17 may occupy any position intermediate these two extremes.

While I might make use of the plate 17 as a supporting plate for the dishes of food by not having the slots 18 extend through it but only undercut from the bottom still I 20 prefer, in practice, to have this plate support a top plate for the real arm of the chair for supporting the dishes of food. Thus I have shown a top plate 19 which may be of wood, aluminum, or any desired 25 material. The shape of this plate appears clearly from Figs. 1 and 2 from which it will be seen to extend at least slightly over the periphery of the plate 17. In order that the plate 19 will be carried sufficiently above the 30 plate 17 so as to provide clearance for the heads 15 of the bolts 13 I support it from the plate 17 through the medium of blocks 20 located at various points on the upper surface of the plate 17 and through which are adapted to pass, from the under surface of the plate 17, screws 21 for securing the 35 parts 19, 20 and 17 together. The holes in the plate 17 are countersunk from the underside so that the heads 22 of the screws 21 will, when the latter are completely in place, 40 be flush with the bottom surface of the plate 17 so as to form no obstruction against the sliding of the plate 19 over the top surface 10 of the bracket 2. Thus the parts 19 and 45 17 are in effect one so far as operation is concerned, and these two together with their connecting elements form the adjustable chair arm, these parts sliding when desired over the surface of the top 10 of the bracket 50 2 guided by the bolts 13 which in coöperation with the slots 18 determine the path through which the adjustable arm is to pass. The length of the slots 18 of course determines the extent of adjusting movement 55 over which the arm may pass.

In Fig. 2 I have indicated at one corner of the chair at the back a vertical apparel hanger 23 which may be mounted on the back of the chair by screws or other means, 60 and this I preferably provide at the top with a hook 24 adapted to receive any article of apparel desired to be disposed of temporarily while one is using the chair for his lunch. This provides for keeping his apparel within sight so that it will not be in 65

any danger of being intentionally or unintentionally taken by other parties.

It is believed that the operation of my invention will be clear from the above description. It may be briefly stated, however, 70 that generally in using a chair with my invention applied, the dishes of food will be placed upon the top plate 19 of the adjustable arm with it in position shown in Fig. 1 before the patron sits down in the chair. 75 After he sits down and has placed his desired apparel upon his individual hook 24 at the back of the chair all that is necessary to bring his food around to the front of him for more convenient eating, is for him to 80 catch hold of the plate 19 and slide it forwardly, which movement owing to the shape of the slots 18, will be effective to position the arm 19 with his food at his front as shown in Fig. 2. The bracket 2 does not 85 move in these operations but remains fixed as a convenient and substantial support for the adjustable arm for the chair. When the patron is through eating the arm is easily shifted back to the position at the 90 right of the chair shown in Fig. 1 permitting more convenient arising of the patron from his chair.

From the drawings it will be clear that the shape of the arm and coöperating parts 95 and the radius and relationship of the slots 18 is such that the adjustable arm in swinging from one extreme to another, never projects at one time farther to the right of the chair than at any other time. By this construction the danger of interfering with the user of the next chair to the right is eliminated and the necessary space between the chairs is therefore kept down to a minimum.

It will be observed that my invention has 100 been applied in a very simple and efficient way suitable for application to the old form of chairs now in use as it is for application to the new form of chairs. While very simple in construction it is likewise efficient 105 in service. I have shown a preferred form of construction but I do not mean to be limited thereto except as required by the scope of the appended claims for the reason that various changes and modifications may readily occur to those skilled in the art all coming within the principle of my invention as herein disclosed.

Having described my invention, what I claim as new and desire to secure by Letters 120 Patent is:—

1. A device of the class described comprising the combination of a supporting bracket, adapted to be secured to the side of a chair; an arm, slideable on said bracket, said arm having, on its lower surface, a pair of parallel tracks curved around a center disposed above the seat of the chair, said tracks being substantially parallel to the outer edge of said arm; and guide members, carried by 125 130

said bracket and coöperating with said tracks to limit the movement of the arm to a path predetermined by the curvature of the tracks.

5 2. The combination with a chair, of a supporting bracket carried thereby; an arm slideable thereon; a pair of concentric arcuate tracks carried by said arm; guide members, carried by said bracket, and coöperating 10 with said tracks to limit the movement of said arm to a swinging movement about an axis disposed over the seat of said chair.

3. The combination, with a chair, of an arm supporting bracket, an arm slideable 15 thereon; guiding means on said arm; a guide member on said bracket; said guiding means being substantially parallel to the outer edge of said arm and limiting the movement of said arm to a bodily rotation around a 20 center disposed over the seat of the chair.

4. A device of the class described comprising a bracket, adapted to be detachably secured to the leg of a chair, and having a

horizontal arm support; a pair of guide pins carried by said support and having 25 enlarged heads; a guide plate provided with a pair of parallel slots in which said pins are disposed; and an arm carried by said guide plate above and spaced from the same.

5. A device of the class described comprising an arm support secured to the leg of a chair; a pair of guide pins carried by 30 said support; a guide plate provided with a pair of parallel slots in which said guide pins are disposed; and an arm carried by 35 said guide plate above and spaced from the same.

6. A device of the class described comprising an arm support adapted to be secured to the leg of a chair; guide pins carried by 40 said support and an arm slideable on said support, the movement of said arm being limited by said guide pins to an arcuate path having its center of curvature disposed over the seat of said chair.

PAUL W. HIRSCH.
